US0D1064480S

(12) **United States Design Patent** (10) **Patent No.:** **US D1,064,480 S**
(45) **Date of Patent:** **** Feb. 25, 2025**

(54) **COLLAPSIBLE GREASE BUCKET LINER**

- (71) Applicant: **Jinghe Zhuang**, Zhuhai (CN)
(72) Inventor: **Jinghe Zhuang**, Zhuhai (CN)
(**) Term: **15 Years**
(21) Appl. No.: **29/941,569**
(22) Filed: **May 10, 2024**
(51) LOC (15) Cl. **07-05**
(52) U.S. Cl.
USPC **D32/53; D7/407**
(58) **Field of Classification Search**

(57) **CLAIM**

The ornamental design for a collapsible grease bucket liner as shown and described.

DESCRIPTION

FIG. 1 is a top perspective view of my new design;
FIG. 2 is a bottom perspective view thereof;
FIG. 3 is a perspective view thereof shown in a collapsed position;
FIG. 4 is a front view of my new design shown in an open configuration;
FIG. 5 is a rear view thereof;
FIG. 6 is a left side view thereof;
FIG. 7 is a right side view thereof;
FIG. 8 is a top view thereof; and,
FIG. 9 is a bottom view thereof.
The portions of the collapsible grease bucket liner shown in broken lines form no part of the claimed design. The broken lines immediately adjacent surface shading depict the bounds of the claimed design and form no part thereof.

1 Claim, 9 Drawing Sheets
